RACING GAME DEVICE

Errol D. Jones, New York, N. Y.

Application February 23, 1946, Serial No. 649,671

1 Claim. (Cl. 273—86)

1

This invention relates to game devices, and more specifically to a device which simulates a race between a number of objects representing horses, cars, or the like, controlled by different players in such a way that the relative skill of the players determines the results of the race.

While I illustrate my invention by means of a preferred embodiment wherein the aforementioned racing objects are in the shape of horses, it will be obvious that the structure and operation of my device are in no way affected by the particular shape of the racing objects, and that the word "horses," as used hereafter, must be construed to apply to a full range of equivalents.

An object of my invention is to provide a game device of the class described, which is simple, amusing, sturdy, and very economical to manufacture.

Another object of my invention is to provide a game device which is apt to test and develop the player's coordination, sense of timing, and quick reflexes.

A further object is to provide a game device wherein electromechanical means are employed to operate the racing objects, said means being not only well suited to their purpose, but also amusing and attractive in themselves.

My invention will be understood with reference to the drawings, wherein:

Fig. 1 is a perspective view of the whole device, showing the horses at various stages of the race.

Fig. 2 is a cross-section on the line 2—2 of Fig. 5.

Fig. 3 is a cross-section on the line 3—3 of Fig. 5.

Fig. 4 is a plan view with the cover removed from that part of the device which houses the operating elements, to show said elements at various stages of their operation.

Fig. 5 is a section on the line 5—5 of Fig. 4.

Referring now in detail to the drawings, my device comprises a long box-like frame 1, made of wood or other suitable material, the top part of which constitutes a race track and has a number of grooves or individual tracks 2, in the particular example shown, six of them. On each groove there may be placed a horse. Fig. 1 shows horse 4 at the starting point, horse 3 as near the end of the track, and the remaining horses 5, 6, 7, and 8 at intermediate positions. Each groove is adapted to receive a ball, of steel or any suitable material, such as balls 11, 13, and 14 which are seen in Fig. 1, and balls 9, 10, and 12 seen in Fig. 4.

When the device is in operation, the forward

part of frame 1 rests on feet or legs 15, preferably hinged to the underside of the frame, as indicated at 16, to be swung inside the frame, the purpose of said feet or legs 15 being to confer upon the race track a rearward-downward slant steep enough to cause the balls to roll backwards in the grooves when left to themselves, but not steep enough to overcome the friction between the horses and grooves. The frame 1 also has a front plate 17 closing the end of the race track, and a solenoid box 18 housing what I call the operating elements, which are solenoids, plungers, springs, and contacts. The balls 9 . . . 14 when at rest are also covered by the open front portion of the box 18. Inside the box 18 are solenoids 19, 20, 21, 22, 23, and 24, associated respectively with plungers 25, 26, 27, 28, 29, and 30, and springs 31, 32, 33, 34, 35, and 36. The plungers have in their rear portions vertical slots 37, 38, 39, 40, 41, and 42, partially closed at the rear with twisted wires or similar means 43, 44, 45, 46, 47, and 48. The length of the slots is carefully determined to obtain the particular retarding action which will be hereafter described, and on which the satisfactory operation of the device largely depends. The springs 31 . . . 36 are made of any suitable material, such as piano wire, which has satisfactory properties of lightness and resiliency.

The solenoids are connected through wires generally indicated at 49, push type switches generally indicated at 50, line wire 51, and plug 52, to a source of A. C. or D. C. current. Normally the plungers are all the way to the rear, like the plunger 26 in Fig. 4. Examining this plunger 26, it is seen that the spring 32 associated therewith is near the front end of the slot 38, and the associated ball 10 rests against the associated solenoid 20. The associated horse 4 is placed a little ahead of the ball 10, at the beginning of its track. Those are the positions of all the elements at the beginning of the game.

If now the button 50 is pushed which is associated with a certain solenoid, the solenoid becomes energized and attracts its plunger. The plunger being slotted, does not disturb its associated spring until it has reached the position exemplified by the plunger 28, which has advanced far enough for its end wire 46 to touch the spring 34. Until then, the plunger accelerates and gains momentum freely; thereafter the spring begins to bend and to resist the forward motion of the plunger. Nevertheless the plunger continues to move, eventually reaching the forwardmost position exemplified by the plunger 25. This latter

is shown protruding through the forward end of its solenoid 19, striking its ball 9, and impelling it forward, whereby the ball in turn will strike its horse, and push it on, as the ball 13 is shown as doing in Fig. 1. As soon as the solenoid 19 is deenergized, the spring 31 will force the plunger 25 back until it reaches the position exemplified by the plunger 28, whereafter the plunger will proceed by inertia back to substantially its starting point. The ball, after having pushed the horse, will roll back to rest in its starting position against its solenoid, while the horse will be held by friction in its new position.

The player, in order to win, must keep energizing the solenoid which operates the horse he picked as often and quickly as possible. However, if he pushes his switch button too quickly, the plunger will be all the way forward before the ball has quite returned to its starting point. An instant later the ball is in position, but it will bounce at once again out of position. Thereafter it will rest against the solenoid, but by then its backward momentum is spent, and if the ball is stricken now by the plunger, some time will have been lost. It is an instructive and amusing challenge to the player, this desirability of striking the ball in the split second when it first hits the solenoid in its rear return, before it rebounds, a challenge which tests and develops his sense of timing and his reflexes. The mechanical structure of the propelling mechanism is also very important. Were plungers and spring so connected that motion of the one would immediately produce deformation of the other, the whole device would become sluggish and prone to jam. But thanks to the fact that the plunger is permitted to travel freely for a space, and to acquire a certain momentum before engaging the spring, this latter may be made relatively strong and with a small deformation, rather than weak and with a large deformation, and the plunger is permitted to strike the ball with a smart impact, resulting in an efficient and amusing operation of the latter. Further, the rearward return of the ball being due to gravity, and opposed by the friction of the track, the ball has to be watched keenly by the player up to the moment in which it disappears under the forward part of the box 18. The player has to guess the interval of time which will pass before the ball is in the favorable striking position, and balance it against the delay in the striking, subsequent to his pressing the switch, due to plunger inertia and spring resistance. Thus my device not only provides a real

game of skill, but does so with a structure the simplicity and ruggedness of which, and the resulting economy are quite apparent.

It is to be understood that the foregoing description has been given merely by way of example and that many changes, alternative arrangements, and additions of cooperative and ornamental details, are possible within the spirit of the invention and the scope of the appended claim.

10 I claim:

15 In a game device having an upwardly inclined frame provided with a number of raceways therein, a racing object movable along each raceway thereof and a sphere in each raceway movable in one direction for displacing a racing object therealong and rollable by gravity in the other direction to a starting position; a solenoid supported in the frame at the rear of each raceway, 20 a plunger actuatable by said solenoid and movable from a rear position to a foremost position whereby its foremost end is projected forwardly of said solenoid into the raceway, the forward motion of said plunger upon projection when said solenoid is energized, propelling a sphere in its starting position toward the racing object, said plunger having a slot at its rear, a spring fastened to said frame and projecting into said slot, said spring normally projecting adjacent the front end of 25 said slot when the plunger is in rearmost position and contacting the rear end of said slot when the plunger is in a position intermediate between its rearmost and foremost positions, and 30 means for energizing and de-energizing said solenoid at will.
